LOOM HARNESS

John Jacob Kaufmann, Elkins Park, Pa., assignor
to Steel Heddle Manufacturing Company, Philadelphia, Pa., a corporation of Pennsylvania

Application December 16, 1939, Serial No. 309,545

5 Claims. (Cl. 139—91)

This invention relates to loom harness and more particularly to harness having means for facilitating the separation of the heddles by automatic mechanical means, such, for example, as warp drawing-in mechanism, by means of which the warp ends are drawn through the eyes of the heddles.

Heretofore, helical springs have been employed in connection with loom harness in which the warp was to be drawn in by means of a drawing-in machine, in the successive convolutions of which springs the heddles are individually disposed. These coil springs are operated upon by the selector worm of the drawing-in machine to bring the eyes of the heddles successively to the proper position in alignment with the needle or hook of the drawing-in machine.

However, the mounting of the coil springs in the harness entails considerable expenditure of time and labor, and consequently in some instances the coil springs are left in the harness when the same is mounted in the loom, but at such position therein as will not interfere with the proper shedding of the warp in the loom during the weaving operations.

The principal object of the present invention is to provide loom harness in which the heddles are made of thin flat strips of metal or wire having means for facilitating the mounting therein of the coil spring used in the warp drawing-in operation, and for maintaining said coil spring in such position in the harness as not to interfere with the proper shedding of the warp during the weaving, yet being so constructed and arranged as to permit the coil spring to be readily brought into position adjacent the warp eyes when a warp is to be entered in an automatic warp drawing-in machine.

The nature and characteristic features of the invention will be more readily understood from the following description taken in connection with the accompanying drawing forming part hereof, in which:

Figure 1 is a front elevation of a portion of a loom harness embodying the main features of the present invention, and in which the coil spring, used for effecting the separation and positioning of the warp eyes in a warp drawing-in machine, is shown in position adjacent the warp eyes to facilitate the drawing-in of the warp;

Fig. 2 is a similar view but with coil spring located in the harness in the position occupied by the same during the weaving operation;

Fig. 3 is a side elevation of the structure shown in Fig. 2; and

Fig. 4 is an enlarged detail view of the upper portion of the harness as shown in Fig. 2.

It will, of course, be understood that the description and drawing herein contained are illustrative merely, and that various changes and modifications may be made in the structure disclosed without departing from the spirit of the invention.

Referring to the drawing, in the particular embodiment of the invention therein shown, 10 and 11 are the usual heddle supporting rods which, as is well known to those skilled in the art, are mounted in suitable frames of any preferred construction.

15 The heddles 12 are made from thin flat strips of metal or wire having mortises 13 and 14 adjacent their respective ends for mounting the same on the supporting rods 10 and 11. Each of the heddles 12 is also provided with a warp eye 15, the preferred location of which will be hereinafter set forth. The mortises 13 and 14 and the warp eyes 15 are formed in the heddles in the usual and customary manner.

20 The harness is also provided with means for spacing the heddles. The preferred spacing means, as shown in the drawing, comprises the provision in each alternate heddle of an offset out of the main plane of the heddle in an elongated S-shaped conformation, the other alternate heddle being flat at this portion, so that when the heddles are closely assembled in the frame, the offset portions will serve to space the heddles equally. This arrangement is provided, as at 17, near the top adjacent the mortises 13 25 for mounting the upper ends of the heddles 12 on the supporting rod 10, and preferably also near the bottom, as at 18, adjacent the mortises 14 for mounting the lower ends of the heddles on the supporting rod 11.

30 There is also provided an additional set of spacing offsets 19 located a sufficient distance from the upper set of offsets 17 to permit the insertion of the coil spring 20 which is employed for the purpose of assisting the selector worm of the drawing-in machine in bringing the warp eyes 15 of the individual heddles to the proper position for the passage therethrough of the drawing-in or entering needle or hook.

35 The set of spacing offsets 19 is also of an elongated S-shape, having a portion extending on each side from the main plane of the heddle to coact with the flat portions of the adjacent alternate heddles at this point. Also, where the end portions of the S-shaped offset join the adjacent straight portions of the heddle, the

same extend in slight curvatures thus avoiding any sharp corners, for a reason presently to be explained.

A loom harness constructed as above described will greatly facilitate the various operations in connection with the entering or drawing-in of the warp. It will, of course, be understood that even when the coil spring 20 is not employed, the equally spaced straight portions 21 extending between the set of offsets 17 and the set of offsets 19 will greatly facilitate the manual selection of the heddles where the entering is done by hand.

However, the invention finds its greater usefulness in the employment of the coil spring 20 which permits the warp to be entered or drawn in by an automatic machine. When the coil spring 20 is employed, the accurate spacing of the straight portions 21 between the offsets 17 and the offsets 19 permits the ready positioning of the coil spring 20 with respect to the heddles 12, as the successive convolutions of the spring 20 may thereby be more easily brought into engagement with the individual heddles at this point, as shown in Figs. 2 and 4 of the drawing.

When the warp is to be entered by means of a drawing-in machine, the coil spring 20 may readily be shifted downwardly on the heddles, the peculiar formation of the spacing devices 19 permitting the spring 20 to pass without too much obstruction. The spring 20 is brought to the position shown in Fig. 1 of the drawing, adjacent the warp eyes 15, so that the selector worm of the drawing-in machine may operate thereon and bring the warp eyes 15 of the heddles 12 successively to the operative position for entering the warp therein.

After the warp has been entered, the coil spring 20 is then pushed upwardly and returned to the position shown in Figs. 2 and 3 of the drawing, and said spring 20 normally will be held at this position during the operation of the harness in the loom by reason of the offsets 19 offering sufficient resistance against the downward movement of the coil spring 20 to retain the same during the shedding operations.

It should also be understood that the warp eyes 15, instead of being located midway between the mortises for mounting the heddles 12 on the supporting rods, are in the present instance preferably located substantially midway between the lower set of offsets 17 and the set of offsets 19 which serve to retain the coil spring 20 in the raised position above the shed line of the harness during the operation in the loom. By this arrangement, the largest possible shed opening may be obtained without fouling the warp on either set of the offsets.

I claim:

1. Loom harness having upper and lower heddle supporting rods, flat metallic heddles mounted thereon, means for spacing said heddles comprising the provision on alternate heddles, adjacent the upper supporting rod, of offsets extending out of the main plane of the heddle on each side thereof, an additional set of similar offsets below the upper set, and a coil spring in the successive convolutions of which the heddles are individually disposed, and said coil spring being movable to a position adjacent the warp eyes of the heddles for entering the warp in said eyes, the offsets in the heddles each being of the conformation of an elongated S with its ends curving into straight portions of the heddle, and

the lower set of said offsets being spaced from the upper set a sufficient distance to receive the coil spring therebetween and normally retain the coil spring above the upper shed line of the harness.

2. Loom harness having upper and lower heddle supporting rods, flat steel heddles mounted thereon, means for spacing said heddles comprising the provision on alternate heddles, adjacent the upper supporting rod, of offsets extending out of the main plane of the heddle on each side thereof, an additional set of similar offsets below the upper set, and a coil spring in the successive convolutions of which the heddles are individually disposed, said coil spring being adapted for use in the selector mechanism of a warp drawing-in machine, and said coil spring being movable to a position adjacent the warp eyes of the heddles for entering the warp in said eyes, the offsets in the heddles each being of the conformation of an elongated S with its ends curving into straight portions of the heddle, and the lower set of said offsets being spaced from the upper set a sufficient distance to receive the coil spring therebetween and normally retain the coil spring above the upper shed line of the harness.

3. Loom harness having upper and lower heddle supporting rods, flat metallic heddles mounted thereon, means for spacing said heddles comprising the provision on alternate heddles, adjacent the upper and lower supporting rods, of offsets extending out of the main plane of the heddle on each side thereof, an additional set of similar offsets below the upper set, and a coil spring in the successive convolutions of which the heddles are individually disposed, and said coil spring being movable to a position adjacent the warp eyes of the heddles for entering the warp in said eyes, and the said additional set of offsets being spaced from the upper set a sufficient distance to receive the coil spring therebetween and normally retain said coil spring above the upper shed line of the harness.

4. Loom harness having upper and lower heddle supporting rods, flat metallic heddles mounted thereon, means for spacing said heddles comprising the provision on alternate heddles, adjacent the upper and lower supporting rods, of offsets extending out of the main plane of the heddle on each side thereof, an additional set of similar offsets below the upper set, and a coil spring in the successive convolutions of which the heddles are individually disposed, said coil spring being adapted for use in the selector mechanism of a warp drawing-in machine and being movable to a position adjacent the warp eyes of the heddles for entering the warp in said eyes, and the said additional set of offsets being spaced from the upper set a sufficient distance to receive the coil spring therebetween and normally retain said coil spring above the upper shed line of the harness.

5. Loom harness having upper and lower heddle supporting rods, flat metallic heddles mounted thereon, means for spacing said heddles comprising the provision on alternate heddles, adjacent the upper and lower supporting rods, of offsets extending out of the main plane of the heddle on each side thereof, an additional set of offsets below the upper set, and a coil spring in the successive convolutions of which the heddles are individually disposed, said coil spring being adapted for use in the selector mechanism of a warp drawing-in machine and being

movable to a position adjacent the warp eyes of the heddles for entering the warp in said eyes, the additional set of offsets being spaced from the upper set a sufficient distance to receive the coil spring therebetween and normally retain said coil spring above the upper shed line of the

harness, and the warp eyes being located in the heddles substantially midway between the set of offsets adjacent the lower supporting rod and the aforesaid additional set of offsets.

JOHN JACOB KAUFMANN.
